W. K. HOWE

WASHING MACHINE CYLINDER

Original Filed May 4, 1922

INVENTOR.
W. K. Howe
By Neil H. Weston
his ATTORNEY

UNITED STATES PATENT OFFICE.

WINTHROP K. HOWE, OF ROCHESTER, NEW YORK, ASSIGNOR, BY MESNE ASSIGNMENTS, TO GENERAL RAILWAY SIGNAL COMPANY, OF ROCHESTER, NEW YORK, A CORPORATION OF NEW YORK.

WASHING-MACHINE CYLINDER.

Original application filed May 4, 1922, Serial No. 558,418. Divided and this application filed March 31, 1926. Serial No. 98,831.

This invention relates to washing machine clothes drums or cylinders of the type which are rotated or oscillated in a suitable tub of water when in use, and more particularly to 5 the cover or closure means thereof.

Clothes cylinders or drums of this kind have commonly been made entirely of wood, because they are cheap, do not readily corrode, and are not affected by electrolytic 10 action. The wooden cylinders, however, are heavy, especially when wet, and also tend somewhat to warp and change in shape in accordance with the amount of moisture absorbed by them.

15 In the present invention it is proposed to have the cylinder and cover made up mostly of metal of a suitable weight and strength and also have qualities which will prevent electrolytic action when immersed in water 20 containing commercial soaps and washing powders.

The principal objects of this invention are to provide a cover that does not project beyond the circular periphery of the washing 25 machine cylinder or drum when in place, and which may be readily put in place and held firmly while the cylinder is in motion and can be quickly and easily removed for the purpose of changing the clothes when the 30 cylinder is not in motion.

Other objects and purposes of the invention will appear as the description progresses.

This application is a division of my prior 35 application, Serial No. 558,418, filed May 4, 1922.

In describing the invention in detail, reference will be made to the accompanying drawing, in which:—

40 Figure 1 is a sectional view of a washing cylinder embodying the present invention, taken through the axis thereof;

Fig. 2 is an end view of the driving end of the cylinder, portions thereof being broken away to illustrate the construction of the cover;

Fig. 3 is a section taken on the line 3—3 in Fig. 2, as viewed in the direction of the arrows; and

50 Fig. 4 is an enlarged view of the end of the cover, as shown in the section broken away in Fig. 2.

The particular construction of the cylinder or drum illustrated comprises in general, two circular end walls or plates E, constructed of any suitable metal, but preferably comprising sheet aluminum which is bent into shape as shown. These circular end walls E are provided with a flange 1, 55 preferably spun or rolled thereon, and extended substantially perpendicular and toward the outside of these walls. The end of the flange 1 is spun or rolled back to form a partially closed bead 2, thereby eliminating sharp edges which might injure the operator, or tear the clothes when filling the washing cylinder or wringing clothes therefrom. This bead 2 formed on each of the end walls E is, however, left partly open to receive the edge of the cylindrical wall 3 60 of the washing cylinder. This cylindrical wall 3 preferably extends around the end walls E a distance to leave an opening sufficiently large for filling the clothes cylinder and wringing clothes therefrom. This cylindrical wall bears against the flange 1 integral with the end walls E, and extends into the open part of the bead 2. After this wall 3 has been slipped into the beads 2 in this manner, holes are drilled through the wall 3 and the flange 1 for receiving the rivets 4. 65 The remaining portion of the beads 2, which forms the sides of the opening in the cylinder, is bent down or closed upon the outer face of the flange 1, as shown at 5.

In order to properly work the clothes in the water as the cylinder rotates or oscillates, suitable lifters are provided at desired points around the inside of the drum. These lifters may be made of any suitable material, and have in the present instance been shown as comprising wooden slats or boards 6, fastened radially at five substantially equally spaced points about the inner circumference of the cylinder. These lifters are secured in place in any suitable manner, and have been shown fastened by nails 7. The opening through which the clothes are adapted to be put into the cylinder preferably extends between two of these lifters 6.

One of the end walls E is provided with a star-shaped plate 8, fastened thereto by rivets 9, having a bearing boss or stud 10 integral therewith. This stud 10 is adapted

to cooperate with a suitable bearing for supporting this end of the cylinder when in operation. The other end wall E is provided with a similar star-shaped plate 11, 5 fastened in the same manner, which is provided with a similar but larger bearing boss which is hollowed to form a socket or clutch member 12. This socket is preferably tapered, as shown, and of a square, triangular or polygonal cross-sectional configuration.

In practice the washing machine in which this washing cylinder is to be used, is provided with a companion clutch member 15 which has an external shape corresponding to that of the socket 12. This companion clutch member forms the driving means, and is slidably supported so that it may be moved into or out of engagement with the 20 socket or clutch member 12.

The cover for the opening heretofore mentioned is of curved shape to complete the cylindrical wall 3 of the washing cylinder, both as to the internal and external surfaces, 25 and is constructed to bear against the flange 1 of the end walls E of this cylinder. More specifically, this cover 13 comprises a curved piece of sheet metal having its sides bent back on itself, as shown at 14, and is nailed 30 or otherwise suitably fastened to two reinforcing members 15 of a shape corresponding to a segment of the end wall E. The other sides of this cover 13 are rolled around cross rods 16, which are in turn nailed against the 35 ends of the reinforcing members 15 in any suitable manner, as conveniently illustrated by the nails 17.

One of these reinforcing members 15 is provided with a pair of bearing plates 18 40 terminating in bearing pins 19, which are adapted to engage holes provided in one of the end walls E. These bearing plates have been shown fastened to the reinforcing pieces by screws 20. The other reinforcing 45 member 15 is notched to receive the hook 21 of a spring latch member L. The bearing surface of the notch just mentioned is reinforced by a metal plate 23 screw fastened to the reinforcing member 15. The latch member L more specifically comprises a 50 spring 24 riveted to the end wall E having a combined latch and handle riveted to the free end thereof. The handle 25 of this latch member extends from the end of the 55 cylinder so that it is easily accessible, but does not extend farther from the axis of the cylinder than does the bead 2 of the end wall of the cylinder itself thereby permitting the cylindrical portion of the cylinder to move 60 very near the walls of the container. This also eliminates any projections extending from the top of the cylinder when rotating which would be apt to catch the clothes or hand of the operator. The cylindrical portion of the washing cylinder and the cover 65

are preferably perforated, as shown at 26. This is done to allow the free circulation of water between the washing machine container and the cylinder itself.

In order to facilitate the removal of the 70 cover 13, this cover has been provided with an opening in which is riveted an eyelet 27 sufficiently large to allow a finger to be inserted for lifting the cover from the cylinder. In placing the cover into its operative 75 position, the pins 19 are inserted into their corresponding openings, and the other end of the cover 13 is pushed into position, thereby allowing the spring latch member L to lock in position to hold the cover in place.

Having thus fully shown and described one specific embodiment of the invention, I desire to have it understood that various modifications and obvious changes may be made, without departing from the spirit and 85 scope thereof.

What I claim as new and desire to secure by Letters Patent is:—

1. In a cover for washing machine cylinders, a pair of reinforcing members having 90 their ends connected by rods, and a curved metallic wall connected to said reinforcing members and rods.

2. The combination of a washing machine cylinder having a part of its cylindrical wall omitted to serve as an opening, and a cover for said opening comprising a pair of reinforcing members, a curved wall attached to said members and projecting beyond the edges thereof to form supports, means extending from one of said reinforcing members adapted to engage a hole in the cylinder, and a spring-pressed hook at the other end of the cylinder adapted to engage the other of said members.

3. A washing machine cylinder having circular end walls and a cylindrical wall, a part of the cylindrical wall being omitted to serve as an opening, and a cover for said opening comprising a pair of reinforcing members, rods connecting the ends of said reinforcing members to form a rectangle, a curved metallic wall overlying said members and extending around said rods and fastening means secured to one of said reinforcing members and extending through openings in one of said end walls of said cylinder.

4. A washing machine cylinder having flanged circular end walls and a cylindrical wall, a part of the cylindrical wall being omitted to serve as an opening, and a cover comprising a pair of end reinforcing members, a curved wall attached to said members and projecting beyond the edges thereof to engage the flange on said circular end walls, plates carrying bearing pins secured to one of said reinforcing members, said pins engaging openings in one of said end walls, and a spring pressed hook passing 120

through an opening in the other of said end walls and engaging the other of said reinforcing members.

5. A washing machine cylinder having flanged circular end walls and a cylindrical wall, a part of the cylindrical wall being omitted to serve as an opening, and a cover comprising a pair of end reinforcing members, a curved wall attached to said members and projecting beyond the edges thereof to engage the flange on said circular

end walls, projecting means carried by one of said reinforcing members and engaging openings in one of said end walls, and a spring pressed hook passing through an opening in the other of said end walls and engaging the other of said reinforcing members, said hook having an integral handle extending outside of the end wall. 15

In testimony whereof I hereby affix my 20
signature.

WINTHROP K. HOWE.
